UNITED STATES PATENT OFFICE.

GEORGE L. DU LANEY, OF BROOKLYN, NEW YORK.

DESIGN FOR SEWING-MACHINE COVERS.

Specification forming part of Design No. 6,210, dated October 22, 1872.

To all whom it may concern:

Be it known that I, GEORGE L. DU LANEY, of the city of Brooklyn, in the county of Kings and State of New York, have invented a Design for a Sewing-Machine Cover or Box, of which the following is a specification:

The nature of my design is fully represented in the accompanying drawing, to which reference is made.

A represents the box adapted to cover a sewing-machine. It is made with its ends curved or rounded, as shown at *b b*, instead of square, as customary. Its sides are preferably parallel, or nearly so, though they may, if desired, have also a curvature; the essen-

tial character of my design consisting in the round or curved ends. The moldings, when used, will also partake of the general curved form of the box.

I have shown in the drawing a mirror set in the front of the box, and which tends still further to ornament it. This may be used or not, as preferred.

What I claim as my invention is—

A design for a sewing-machine box or cover, substantially as shown and described.

GEORGE L. DU LANEY.
